UNITED STATES PATENT OFFICE.

OSCAR D. GIBBS, OF SPOKANE, WASHINGTON.

BOX-LID PRESSER.

1,105,900.

Specification of Letters Patent. Patented Aug. 4, 1914.

Application filed February 9, 1914. Serial No. 817,556.

To all whom it may concern:

Be it known that I, OSCAR D. GIBBS, a citizen of the United States, residing at Spokane, in the county of Spokane, and State of Washington, have invented new and useful Improvements in Box-Lid Pressers, of which the following is a specification.

This invention relates to improvements in lid pressers, which are especially adapted for use in clamping the lids of fruit boxes to nail the cleats in the operation of securing the lids to the boxes.

It is an object of my invention to provide a lid press, which will clamp the lid upon the box, irrespective of material variations of size thereof and irrespective of the extent of bulge of the lid caused by the contents, so that the cleats will be held in tight relation to permit of nailing the same and the cover to the box.

A further object of my invention relates to an improved yielding support, whereby sufficient yield of the box is afforded to permit of cleating the lid and permitting the mechanism to be moved into a final or locking clamp position.

Other features and objects of the invention will be more fully described in connection with the accompanying drawing, and will be more particularly pointed out and ascertained in and by the appended claims.

In the drawing:—Figure 1 is a perspective view of my improved lid press with the box omitted. Fig. 2 is a view in side elevation with the box in position. Fig. 3 is a view similar to Fig. 2 showing the lid clamped or pressed into position.

Like characters of reference designate similar parts throughout the different figures of the drawing.

As illustrated, my improved lid press includes a yielding base, which may comprise spring boards 1 supported by transverse members 2 in an elevated position with respect to the surface on which the press is disposed so as to permit the boards 1 to slightly spring or yield under action of the device. The spring boards 1 are connected by transverse members 3 and 2, by means of nails or the like, so as to form a unitary yielding base structure. A support 4, which may be in the form of a transversely dis-

posed block rigidly secured to the spring boards 1, is shown disposed centrally between the ends thereof, and is preferably rigid and unyielding and may be formed of wood. Fixed upon the support 4 is a box rest which is desirably yielding and which may comprise longitudinally disposed spring boards 5, fixed to the support 4 in any desired manner. I connect the rest spring boards 5 by cleats 6 and upon the cleats 6 I may dispose angle irons 7 having end flanges 8 for receiving the box 9. When the box 9 is positioned between the angle irons 7, I may slide the same laterally until it engages the end flanges 8 whereupon the box will be correctly positioned for cleating the lid. On opposite sides or ends of the box rest I movably or pivotally mount clamping devices, which may comprise cleat clamps slidably mounted on the carriers and handle means for moving the clamps into an operative position.

In the particular form shown, 10 designates pivot mountings of U-shaped construction in which the lower ends 11 of carrier rods 12 are pivotally mounted, said lower ends being cranked for disposition into the apertured terminals of said U-shaped mountings. Handle links 13 are pivotally mounted on the crank terminals 11 and springs 14, connected with the handle links 13 at 15 normally serve to move the handle links into an upright position. The cleat clamping devices may comprise iron straps 16 having bent-over clamping terminals 17, which may be provided with cleat holding spurs 18, depending therefrom. I have shown the straps 16 riveted to transverse angle iron 19, and I aperture the flanges 20 thereof for slidable projection therethrough of the carrier rods 12. The lower ends of the straps 16 may be extended, as indicated at 21 for pivotal connection therewith of handle bars 22, the outer ends of which may be connected by rods 23.

The handle links 13 are pivoted to the handle bars 22, as indicated at 24, and the handle bars 22 are held in position, as shown in Fig. 1, which is an inoperative position by means such as retainers pivoted at 25 to the transverse members 3. The retainers may comprise handle portions 26 and hooks

27, the latter serving to engage the handle rods 23, as shown in Fig. 1.

In operation, the box 9 is disposed in the position shown in Fig. 2 and the retainers 5 are shifted to release the handle rods so that the springs 16 can shift the clamping devices from the position shown in Fig. 1 to the upright position shown in Fig. 2. It is usual 10 to nail on the lids of fruit boxes by applying cleats to the lids and driving the lid nails through the cleats and lid into the body of the box. I may position the lid cleats by slipping them between the straps 16 and the spurs 18, as shown in Fig. 2. The handles 15 22 are then grasped and raised, as indicated in dotted lines in Fig. 3, to the position shown in Fig. 3, in full lines. This will dispose the pivoted parts on or over a dead center so as to lock and hold the cleat clamps 20 in tight engagement with the lid to press the same upon the box for nailing purposes.

Boxes of this character vary considerably 25 in size, and a feature of my invention which is of great importance in accommodating variations of size, is the yielding box rest 30 which overhangs the block 4 and which permits of downward movement of the ends of the box sufficiently to permit the pivoted parts to be swung onto or across a dead 35 center even in view of a maximum variation in size. A further feature of importance consists in providing a yielding base, such as the spring boards 1, which permit the block 4, under its load, to sag the base 40 and thereby further assist the clamping devices in being shifted into a dead center 45 clamping or press adjustment.

It is believed that the advantages and 50 utility of my invention will be clearly understood from the foregoing description, and while I have herein shown and described one specific form of my invention, I do not wish to be limited thereto except for such limitations as the claims may import.

45 I claim:

1. In a box lid presser, a yielding base, a support on said base, a yielding box rest 55 mounted on and overhanging said support, cleat lid clamping devices pivotally mounted on said base and comprising carriers, clamps 60 slideable on said carriers, and handle lever means having pivotal connection coincident with the pivotal connection of the said clamping devices with said base and pivotally connected with said clamping devices to move the latter into clamping relation with said box lid, substantially as described.

2. In a box lid presser, a support, a yielding box rest mounted on said support, cleat 65 lid clamping devices pivotally mounted on a support and comprising carriers, clamps slideable on said carriers, and handle lever means having pivotal connection coincident with the pivotal connection of said clamp-

ing devices and pivotally connected with 65 said clamping devices to move the latter into clamping relation with said box lid, substantially as described.

3. In a box lid presser, a yielding base, a support on said base, a yielding box rest 70 mounted on said support and overhanging the same to support a box, and cleat clamping devices mounted on said base for clamping the lid on said box, substantially as described. 75

4. In a box lid presser, a yielding base, a support on said base, a yielding box rest mounted on said support and overhanging the same to support a box, and cleat clamping devices mounted independently of said 80 box rest for clamping the lid on said box, substantially as described.

5. In a box lid presser, a yielding base, a support on said base, a yielding box rest mounted on said support and overhanging 85 the same to support a box, cleat clamping devices pivotally mounted on said base for clamping the lid on said box, and pivotal means movable over a dead center for shifting said clamping devices into and holding 90 them into a clamping position, substantially as described.

6. In a box lid presser, a support, a yielding box rest mounted on said support and overhanging the same to support a box, 95 cleat clamping devices pivotally mounted independently of said box rest for clamping the lid on said box, and pivotal means movable over a dead center for shifting said clamping devices into and holding them 100 into a clamping position, substantially as described.

7. In a box lid presser, a yielding box rest, a cleat clamping device for clamping the lid on said box, and means movable over a dead center for shifting said clamping device into and holding it in a clamping position, substantially as described. 105

8. In a box lid presser, a yielding box rest, and pivoted lid clamping means movable past a dead center into a final position to hold the lid and spring said rest, substantially as described. 110

9. In a box lid presser, a yielding box rest, and lid clamping means movable into a 115 clamping position with respect to the box lid to spring said rest, substantially as described.

10. In a box lid presser, a yielding base, a yielding box rest mounted on said base, and lid clamping means mounted on said yielding base, substantially as described. 120

11. In a box lid presser, a yielding base, a yielding box rest, a rigid element supporting the box rest on the base, and lid clamping means mounted on said yielding base, substantially as described. 125

12. In a box lid presser, a yielding box

rest, and yieldingly mounted lid clamping means movable into a clamping position to spring said rest, substantially as described.

13. In a box lid presser, a box supporting structure having resilient portions yielding under the weight of a box, and lid clamping means for holding a lid upon a box supported by said structure, substantially as described.

10 14. In a box lid presser, a box supporting structure having end portions resilient

under the weight of a box, and lid clamping means for clamping a lid upon a box supported by said structure, substantially as described.

15 In testimony that I claim the foregoing as my own, I hereby affix my signature in the presence of two subscribing witnesses.

OSCAR D. GIBBS.
